DESIGN FOR AN EMBROIDERED TEXTILE FABRIC

Harris A. Rohtman, New York, N. Y.

Application May 23, 1939, Serial No. 85,144

Term of patent 3½ years

To all whom it may concern:

Be it known that I, Harris A. Rohtman, a citizen of the United States of America, residing in the city of New York, county of New York and State of New York, have invented a new, original, and ornamental Design for an Embroidered Textile Fabric, of which the following is a specification, reference being had to the accompanying drawing, forming part thereof.

The figure shows a plan view of an embroidered textile fabric, showing my new design.

I claim:

The ornamental design for an embroidered textile fabric, substantially as shown.

HARRIS A. ROHTMAN.
